UNITED STATES PATENT OFFICE

2,247,862

OPERATING MECHANISM

Carl Thumim, Yeadon, Pa., assignor to General
Electric Company, a corporation of New York

Application April 3, 1940, Serial No. 327,624

6 Claims. (Cl. 200—89)

My invention relates to operating mechanisms for electric circuit breakers of the reclosing type and more particularly to operating mechanisms which are so constructed and arranged that very high-speed reclosing of the circuit breaker is possible.

It has been found that perhaps 75 or 80 per cent of the abnormal current conditions or faults which initiate operation of protective apparatus, such as circuit breakers, are temporary and, furthermore, of very short duration. For example, abnormal current surges in transmission lines due to lightning often die out within a few microseconds. It would be desirable in order to maintain good continuity of service for the protective apparatus to distinguish between such temporary or transient faults and prevent the circuit breakers from tripping under such conditions. The above problem may be substantially solved by high-speed reclosing circuit breakers which reclose within a very short interval of time so that the synchronism of the system is not disturbed.

One of the factors which limits the minimum time necessary for the reclosing of circuit breakers is the time required for resetting the tripping linkage which holds the circuit breaker in the closed position. In the prior art arrangements, the entire linkage is reset at once so that, in order to decrease the resetting time, arrangements have been proposed wherein large accelerating forces have been provided in the shape of springs or the like. In such arrangements, the resetting time is decreased at the expense of sensitivity of the protective system since the heavier springs require stronger tripping forces. In accordance with my invention, rapid reclosing of the circuit breaker is made possible by preresetting as many of the heavy parts of the tripping linkage immediately after the tripping action is initiated and during the opening stroke of the circuit breaker so as to leave only a latch of negligible mass finally to be reset when the circuit breaker is reclosed, whereby excessively large springs can be avoided and yet resetting time reduced.

It is an object of my invention, therefore, to provide a new and improved operating mechanism for a very high speed reclosing circuit breaker which is simple and economical in construction to the extent that a minimum of moving parts are involved and which is efficient and reliable in operation.

It is another object of my invention to provide a new and improved operating mechanism for

electric circuit breakers in which the resetting linkage which is slow to reset is reset during the breaker opening stroke so as to be in readiness for immediate reclosing of the circuit breaker.

5 Further objects and advantages of my invention will become apparent as the following description proceeds and the features of novelty which characterize my invention will be pointed out with particularity in the claims annexed to

10 and forming a part of this specification.

For a better understanding of my invention, reference may be had to the accompanying drawings in which Fig. 1 is an elevational view partly in section of a circuit breaker operating mechanism embodying my invention, Fig. 2 is an enlarged perspective view of a portion of the apparatus illustrated in Fig. 1, Fig. 3 represents an operating mechanism embodying a modification of my invention, while Figs. 4 and 5 are modifications of the arrangement illustrated in Fig. 3.

15 Referring more particularly to Fig. 1, the operating mechanism shown therein comprises an actuating means or solenoid 10 for actuating a reciprocally guided rod 11 which, for example, 20 may be connected to operate a suitable circuit breaker, not shown. A collapsible force-transmitting structure 12 interconnects actuating means 10 and actuated means or rod 11. The collapsible force-transmitting structure 12 per se 25 forms no part of the present invention and is illustrated as of the character disclosed and claimed in my United States Letters Patent No. 2,112,054 granted March 22, 1938, and assigned to the same assignee as the present invention.

30 Although a description of the collapsible force-transmitting structure 12 is available in the above-mentioned patent, a brief description thereof will be included hereinafter. Solenoid 10 is provided with an armature 13 which is 35 connected to rod 11 by a chain linkage 14 normally guided on a grooved roller 15 carried by a bell crank 16 pivotally mounted at 17. When the bell crank 16 is held in the position shown by means of a latching mechanism generally

40 indicated at 18 and described in greater detail hereinafter, energization of solenoid 10 causes downward movement of armature 13 and closing movement of the circuit breaker, not shown, associated with rod 11 against the bias of energy-

45 storage means 19, the release of which causes high-speed opening of the associated circuit breaker. In order that energy-storage means 19 50 may remain charged after solenoid 10 is deenergized, I provide a suitable prop 20 spring biased at 21 which cooperates with pin 22 so that arma-

ture 13 is held in its lower position. By this arrangement, the circuit breaker may be held in the closed position by the cooperative action of the prop 20 and latching means 18, the latter cooperating with roller 23 associated with crank 16. It will be understood that solenoid 19 is provided with a suitable control circuit to energize it for automatic reclosing after tripping of the circuit breaker.

With the apparatus in the position indicated in Fig. 1, the release of latching means 18 from restraining roller 23 and hence bell crank 16, would allow the energy stored in the spring 19 due to the force on grooved roller 15 acting through the moment arm indicated at *a*, cause a clockwise rotation of the bell crank 16 to the position shown in dotted lines in Fig. 1. A comparatively sensitive tripping device for latching means 18 can be used if desired since the required tripping force is directly related to the length of the moment arm indicated at *a* through which the resultant reacting force at the chain linkage tends to produce clockwise rotation of bell crank 16. Where the lever arm *a* is quite small, the latch-releasing force required is obviously small.

In order that resetting of the collapsible force-transmitting structure 12 may occur as soon as the tripping action of the circuit breaker is initiated, bell crank 16 is provided with a portion 16' which serves as a cam member for engaging the extension 24 suitably welded to prop 20. Hence, after a predetermined rotation of bell crank 16, the member 24 is engaged and prop 20 is moved to free pin 22, whereby the energy in spring 25 is released to cause an upward movement of armature 13 of solenoid 19. This affords additional slack in chain linkage 14 so that bell crank 16 can immediately reset to the position shown in solid lines in Fig. 1 and, due to the energy stored in spring 26 when bell crank 16 is rotated in the clockwise direction. The above-described arrangement is substantially identical with the apparatus described and claimed in my above-mentioned United States Letters Patent.

In order to save time in the resetting of latching means 18, with which my invention is particularly concerned, I provide an arrangement wherein the parts which are slow to reset do so immediately after the tripping action and during the opening stroke of the circuit breaker so that only a relatively light part must be finely reset when the breaker is reclosed. Latching means 18 shown in an enlarged perspective view in Fig. 2 includes a collapsible member including pawl 27 of negligible mass and to a limited extent relatively movable with respect to the remaining portions of latching means 18 which comprise shaft 28 provided with an offset arm or extension 29 rigidly fastened thereto as by suitable fastening means 30. Offset arm 29 is adapted to engage or coact with the plunger 31 of the conventional tripping solenoid 32. A suitable stop 33 is provided for limiting the downward movement of offset arm 29 and a relatively light spring-biasing means 34 may be provided if desired for resetting shaft 28 and offset arm 29 when tripping solenoid 32 is no longer energized.

Since shaft 28 and extension 29 are relatively heavy, they have considerable inertia and require a relatively long time within which to reset after a tripping movement thereof especially in view of the fact that spring means 34 should be relatively weak so that a very small tripping force from plunger 31 may cause tripping of the circuit breaker. In order to form the collapsible

member of latching means 18, pawl 27 is mounted for limited rotation on shaft 28 by being provided with an enlarged segmental keyway 35 cooperating with a key 36 suitably fitted into shaft 28. The segmental keyway 35 is of such a size as to allow sufficient relative rotation between pawl 27 and shaft 28 when the resetting of bell crank 16 occurs so that the relatively heavy portions 28 and 29 of the collapsible member of latching means 18 need not be disturbed after having been reset. A relatively heavy spring 37 is provided to cause pawl 27 to return to restrain roller 23 immediately after bell crank 16 has been reset.

Manual tripping of the latching means 18 is suitably provided by means of a lever 38 independently pivotally mounted on shaft 28 and co-acting with a pin 39 carried by the extension 29. A manually operable link 40 is connected to the lever 38 for rotating the latching means 18 clockwise in the manner above described.

The operation of the apparatus illustrated in Fig. 1 and more particularly the operation of the latching means 18 best shown in Fig. 2 will be apparent to those skilled in the art and, therefore, will only be briefly described. It is obvious that actuation of the tripping solenoid 32 due to some abnormal current condition will cause elevation of tripping plunger 31 and clockwise rotation of extension 29 and rigidly attached shaft 28 which latter may be suitably mounted in the housing which surrounds the operating mechanism. Such clockwise rotation of shaft 28 will cause similar clockwise rotation of pawl 27 forming the remaining portion of the collapsible member of latching means 18 since key 36 is engaged with one edge of segmental keyway 35. Such rotation of pawl 27 releases roller 23 whereby bell crank 16 is no longer restrained and the energy stored in spring means 19 is released to cause opening movement of the circuit breaker, not shown. As soon as tripping solenoid 32 is de-energized, the collapsible member comprising pawl 27, shaft 28, and extension 29 begins to reset under the relatively small force of spring 34. This resetting may be accomplished immediately after the tripping impulse and during the opening stroke of the circuit breaker. In order to reclose the circuit breaker, it is merely necessary for pawl 27 of negligible mass to move against the force of its spring 37 relative to shaft 28 so that roller 23 of bell crank 16 may again be restrained by latching means 18. Therefore, high-speed reclosing of the circuit breaker is possible since the relatively heavy and slow parts of latching means 18 are reset early and the final member to be reset is sufficiently small and biased by relatively heavy springs to reset almost instantly after reclosing of the circuit breaker. Furthermore, in the arrangement just described, the relatively heavy spring 37 has no effect in so far as decreasing the sensitivity of the tripping apparatus is concerned.

In certain arrangements, the tripping force available is so small as to be unsatisfactory for tripping an arrangement even like that described above which requires a relatively small tripping force. In such arrangements, it is necessary to include energy-storage means which may be released by a very sensitive tripping force and which, in turn, supply a larger tripping force such as is necessary for tripping a circuit breaker. Because of the additional tripping element required, my invention is particularly applicable to such arrangements wherein the sensitive tripping means which requires a great deal of time

to reset may be reset immediately so that the apparatus is ready for high-speed automatic reclosing. In the arrangements to be described hereinafter, therefore, the sensitive latch is permitted to start resetting immediately after being tripped even though the associated circuit breaker has completed only a small part of its opening stroke.

In Fig. 3, I have illustrated my invention as embodied in an operating mechanism of the impact trip type with electric spring reset means. The operating mechanism comprises an actuating means or solenoid 41 and an actuated means comprising rod 42 which may be operatively connected to a suitable circuit breaker or to any other apparatus to which this operating mechanism may be applied. A collapsible force-transmitting structure 43 interconnects actuating means 41 and actuated means or rod 42. The collapsible force-transmitting structure 43 per se forms no part of the present invention and is illustrated as of the character disclosed and claimed in my United States Letters Patent No. 1,988,237, granted January 15, 1935, and assigned to the same assignee as the present invention.

Although a description of the collapsible force-transmitting structure 43 is available in the above-mentioned patent, a brief description thereof will be included hereinafter. Collapsible force-transmitting structure 43 is trip free in operation, that is, the rod 42 may be released at any time during or after the closing stroke of solenoid 41 and comprises a member or link 44, one end of which is pivoted at 45 while its other end provided with a roller 46 coacts with pivoted latch member 47. Link 44 restrained by latch member 47 forms a mounting for a floating link 48 pivotally carried at 49 by link 44 and operatively connected as at 50 to the rod 42. The floating member 48 is arranged to be rotated about the restraining pivot 49 by means of plunger 51 of solenoid 41 which engages with a roller 52 suitably mounted at the other end of floating member 48, thereby causing positive movement of rod 42 in the downward direction to close the associated circuit breaker. In Fig. 3, rod 42 is shown in its lowermost position which represents the closed position of the associated circuit breaker. In order that rod 42 may be restrained in this lowermost position after solenoid 41 is deenergized, a suitable prop 53 is provided pivotally mounted at 54 and normally biased as by a spring 55 in a clockwise direction so that the supporting edge 56 of prop 53 rides under and supports the roller pin 57. Further movement of prop 53 in the clockwise direction is limited by a stop portion 58 which engages a suitable fixed frame or housing member.

In view of the fact that in large circuit breakers the reacting force between roller 46 and latching member 47 is relatively large, a feeble tripping force would be insufficient to release roller 46 from the restraining action of latch 47. For the purpose of efficiently operating the above-described mechanism when but feeble tripping impulses are available, there is provided an auxiliary tripping unit for providing the force necessary to release roller 46 from the restraining action of latch 47. This auxiliary tripping unit comprises a bell crank 59 pivotally mounted at 60 and having one end thereof connected to a rod 61 through a suitable auxiliary source of tripping energy which, in this case, is illustrated as a spring means 62 arranged to be charged by means of solenoid 63 having its armature 64

connected with rod 61. Solenoid 63 is arranged to be energized from a suitable source of energy 65 through overcenter type switch 66 whenever the energy stored in spring 62 is released to trip latch 47. This is accomplished by connecting over center type switch 66 to armature 64 of solenoid 63 so that, whenever the energy stored in spring 62 is released, overcenter type switch 66 is closed to energize solenoid 63 and recharge 10 spring 62 for the next succeeding tripping action. When spring 62 is released, the rapid upward movement of rod 61 causes counterclockwise rotation of bell crank 59 which is provided with a suitable pin 67 to engage as by impact 15 latch 47 which is held in the position shown in Fig. 1 by means of stop 68. Latch 47 is provided with suitable spring means 69 which may be relatively heavy to cause rapid resetting thereof, in view of the relatively large amount of impact 20 trip energy available from spring means 62.

Bell crank 59 and spring 62 are restrained in the position shown in Fig. 3 by means of a collapsible latching member 70 including a pawl 71 which engages with a roller 72 at one end of bell 25 crank 59. Collapsible member 70 is pivotally mounted at 73 and biased against stop member 74 by spring means 75. Pawl 71, which is of negligible mass relative to the remaining portion of collapsible latching means 70, is pivotally mounted to the latter at 76 and biased to the position shown in Fig. 3 where stop member 20 77 of pawl 71 engages with the edge of the relatively heavy portion of collapsible latching means 70 by virtue of the bias of spring means 78. 35 Spring means 69 and 78 may be relatively heavy to decrease the resetting time of pawl 71 and latch 47. Collapsible latching means 70 by being pivotally mounted at 73 provides a considerable force reduction at the end thereof supporting 40 roller 72 as compared to the force acting at the other end thereof against pawl 71.

Collapsible latching means 70 is restrained in the position shown in Fig. 3 by means of sensitive latch 80 biased to the position shown against 45 stop 81 by a very light spring 82 so that it may be tripped by a feeble thrust from sensitive solenoid 83, which is arranged to engage an extension 84 of sensitive latch 80.

The operation of the apparatus illustrated in 50 Fig. 3 and more particularly the operation of the latching means will be only briefly described hereinafter. Sensitive latch 80 is rotated in a counterclockwise direction in response to a feeble tripping force from solenoid 83 because of the 55 relatively small mass of sensitive latch 80 and also because spring 82 is very weak. Such counterclockwise movement releases collapsible latching means 70 which also rotates in a counterclockwise direction so that roller 72 is no longer 60 restrained and crank 59 is free to rotate under the force of spring 62 which is now released causing pin 67 to strike latch 47 rotating it in a counterclockwise direction so that the collapsible 65 force-transmitting structure 43 will allow the circuit breaker associated therewith to open. Immediately after the initiation of the tripping operation and during the opening stroke of the circuit breaker, collapsible latching means 70 is 70 reset under the influence of its spring 75 and thereafter sensitive latch 80 may reset under the influence of its spring 82. Since these two members are reset relatively early and have considerable time in which to reset, springs 75 and 82 may be relatively light. Overcenter type contact 66 is closed when armature 64 is moved

upwardly to rotate bell crank 59 whereupon solenoid 63 is energized to recharge spring 62 and reset bell crank 59. In view of the fact that latching means 10 is collapsible the resetting of bell crank 59 may take place without disturbing the reset positions of sensitive latch 80 and the relatively heavy portion of collapsible latching means 10 since pawl 71 is free to move relative to the remainder of collapsible member 70 to a sufficient extent to allow roller 72 to reassume the position shown in Fig. 3. When the circuit breaker is reclosed, all of the latching means are then reset except latch 47 which is of relatively small mass and furthermore may be provided with a heavy spring so that the resetting time thereof is negligible and very high-speed reclosing of the circuit breaker is possible.

In Fig. 4, I have illustrated a modification of the arrangement shown in Fig. 3 wherein the electric spring reset means is replaced by a mechanical spring reset means. The corresponding parts of Figs. 3 and 4 are designated by the same reference numerals. In this arrangement, spring means 62 for supplying the impact tripping force is arranged to be charged during the opening stroke of the circuit breaker, and, hence, during the upward stroke of rod 42. A pin 85 associated with rod 42 is adapted to strike one end of lever 86 pivotally mounted at 87, the other end of which is connected to rod 61 for compressing spring 62. The operation of this arrangement in other respects is identical with that disclosed in Fig. 3 and no further explanation will be included herewith.

In Fig. 5, I have illustrated the sensitive latching means shown in Figs. 3 and 4 as applied to a back pressure type arrangement similar to that shown in Fig. 1, where no spring tripping force is applied, the force reduction being sufficient in this case so that the sensitive trip may be used. The elements of Fig. 5 which are similar to those of Figs. 3 and 4 are characterized by the same reference numerals. In this case, roller 83 which may be similar to roller 23 of Fig. 1 acting against the inclined surface 89 of bell crank 90 pivotally mounted at 91 gives it a counterclockwise bias which is restrained by the collapsible latching member 78 described above having the pawl 71 thereof engaging with roller 92 at the other end of bell crank 90. Resetting of bell crank 90 is obtained by means of spring 93. The operation of this arrangement will also be obvious to those skilled in the art and it is apparent that, after tripping, the entire system can reset immediately except bell crank 90 and pawl 71, the latter being the only part which must be snapped behind roller 72 at the end of the resetting motion of the collapsible force-transmitting structure, not shown.

In the arrangements disclosed particularly in Figs. 3, 4 and 5, the tripping force available from solenoid 63 is so feeble that it is impossible to use sufficiently heavy springs to reset members 70 and 80 in time for rapid reclosing of the circuit breaker. However, by presetting all the parts which cannot be accelerated by heavy springs as described above, a great deal of time is saved and high-speed reclosing of the circuit breaker is obtained, so as not to disturb the synchronism of an electric distribution system when the tripping of an automatic reclosing circuit breaker is initiated by a fault of very short duration.

While I have shown and described a particular embodiment of my invention as applied to an operating mechanism for an electric circuit break-

er, it will be obvious to those skilled in the art that various changes and modifications can be made without departing from my invention in its broader aspects and I, therefore, aim in the appended claims to cover all such changes and modifications as fall within the true spirit and scope of my invention.

What I claim as new and desire to secure by Letters Patent of the United States is:

1. In an operating mechanism for a circuit breaker of the trip-free type, actuating means and means to be actuated, a collapsible force-transmitting structure interconnecting the aforesaid means, means for latching said force-transmitting structure in the uncollapsed position when the circuit breaker is closed, means responsive to an abnormal electrical condition for tripping said latching means, said latching means comprising a collapsible member including a relatively heavy portion which resets immediately upon tripping of said circuit breaker so that said circuit breaker is in condition for immediate high-speed reclosing and a relatively light portion which resets at high speed upon closing of said circuit breaker.
2. In an operating mechanism for a circuit breaker of the trip-free type, actuating means and means to be actuated, a collapsible force-transmitting structure interconnecting the aforesaid means, latching means for holding said force-transmitting structure in the uncollapsed position when the circuit breaker is closed, means responsive to an abnormal electrical condition for tripping said latching means, said latching means comprising a collapsible member which resets immediately upon tripping of said circuit breaker and which includes a relatively heavy portion and a spring-biased pawl of negligible mass, said pawl being movable relative to said relatively heavy portion so that said circuit breaker may be relatched in the closed position without moving the relatively heavy portion of said latching means whereby high-speed reclosing of said circuit breaker is possible.
3. The combination with an operating mechanism including latching means for holding said mechanism in the closed position, of tripping means for actuating said latching means to cause opening of said mechanism comprising a trip coil sensitive to comparatively small tripping impulses, said latching means comprising a collapsible member which resets immediately upon operation of said tripping means including a relatively heavy portion and a relatively light portion, said relatively light portion being arranged for limited movement with respect to said relatively heavy portion so that said operating mechanism may be reset without disturbing said relatively heavy portion of said latching means.
4. The combination with an operating mechanism including latching means for holding said mechanism in the closed position, of tripping means for actuating said latching means to cause opening of said mechanism comprising a trip coil sensitive to comparatively small tripping impulses, said latching means comprising a collapsible member which resets immediately upon tripping of said circuit breaker and which includes a relatively heavy portion and a spring-biased pawl of negligible mass movable to a limited extent with respect to said relatively heavy portion so that said operating mechanism may be reset without disturbing said relatively heavy portion of said latching means.

5. The combination with an operating mechanism including latching means for holding said mechanism in closed position, of tripping means for actuating said latching means to cause opening of said mechanism comprising a trip coil sensitive to comparatively small tripping impulses, a latch related to said trip coil comprising a collapsible member which resets immediately upon deenergization of said trip coil, said latch being so constructed and arranged as to release energy stored in an energy-storage means whereby a releasing blow is delivered to said latching means under the influence of said stored energy in response to actuation of said trip coil, and means for storing energy in said energy-storage means immediately after the tripping of said operating mechanism.

6. In an operating mechanism for a circuit breaker of the trip-free type, actuating means and means to be actuated, a collapsible force-transmitting structure interconnecting the aforesaid means, latching means for holding said

force-transmitting structure in the uncollapsed position when the circuit breaker is closed, tripping means for actuating said latching means to cause opening of said circuit breaker comprising a trip coil sensitive to comparatively small tripping impulses, a latch related to said trip coil comprising a collapsible member which resets immediately upon deenergization of said trip coil and includes a relatively heavy portion and a portion of negligible mass so constructed and arranged that only said portion of negligible mass is moved when relatching said circuit breaker in the closed position, said latch being constructed to release a spring whereby a blow is delivered to said latching means under influence of the spring energy in response to actuation of said trip coil, and means for causing restressing of said spring during the opening movement of said circuit breaker so that said mechanism is in condition for immediate reclosing of said circuit breaker.

CARL THUMIM.
